MOPSTICK HEAD

Joseph W. Wohlhieter, East Orange, N. J., assignor to Keystone Stamping Corporation, a corporation of New Jersey

Application April 20, 1933, Serial No. 666,990

2 Claims. (Cl. 15—152)

In the construction of cross-heads for mopstick heads it is common practice to provide a notch at each end of the clamping section of the cross-head. These notches form guide 5 grooves for the bail, the legs of which are received therein in the assembled mopstick head. In the closed position of the mopstick head, the clamping section of the bail is held tightly against the clamping section of the cross-head. In the 10 open position of the mopstick head the bail is loose in the notches and there is a substantial amount of play between the bail and the clamping section of the cross-head. In constructions heretofore used, it has been found that during 15 shipment and unpacking of the mopsticks, some of the mopstick heads are opened and the bail member is frequently jarred from the notches in the clamping section of the cross-head. The recipient of such mopstick heads, that is, those in 20 which the bail member is loosened from the notches of the cross-head, returns these mopsticks to the manufacturer at the manufacturer's expense. Likewise, in use, the bail member may become disengaged from the cross-head.

25 An advantage of my invention is the fact that in a mopstick head constructed in accordance therewith, the bail can not become disengaged from the cross-head while the mopstick head is assembled upon a mopstick. In accordance with 30 my invention I provide a cross-head for a mopstick head which includes a socket for the mopstick handle and a transverse clamping section, the clamping section being notched at each end to receive the bail member and including means 35 which partially span the notches and hold the bail member in the notches.

Specifically, the side edge of each of the notches for the bail member formed in the clamping section of the cross-head is undercut 40 on the same side as the operating lever of the mopstick head. The undercut recess forms a groove transverse to the clamping section which receives the corresponding leg of the bail when the mopstick head is in the open position and 45 the tongue formed by the undercut extends into the plane of the bail member in the closed position. The distance between the pivotal connection of the lever to the mopstick handle and the connection of the legs of the bail to the 50 operating lever causes the bail, when the mopstick head is opened, to be inclined to the plane of the mopstick head. In this inclined position the legs of the bail enter and slide in the undercut recesses or grooves in the side edges of the 55 notches from which they can not be displaced.

A mopstick head having a cross-head constructed in accordance with my invention is illustrated in the accompanying drawing and a clearer understanding of my invention may be had from the following particular description of the illustrated embodiment of the invention.

In the drawing:

Fig. 1 is a plan of a mopstick head; and

Fig. 2 is a side elevation.

The mopstick shown in the drawing comprises 10 a handle 1 on which the mopstick head is mounted, the mopstick head including a cross-head 2, a spring 3 surrounding the socket section 2a of the cross-head, a lever 4 pivotally secured to the spring and a bail 5 pivotally secured to the lever 15 at approximately the center thereof and extending in clamping relation with the cross-head. The cross-head 2 is made from a single piece of sheet metal which is stamped into the shape shown. In this shape the cross-head includes a 20 socket section 2a and the transverse clamping section 2b. The face of the clamping section has the usual channel or trough-shape. At each end, the base of the clamping section is notched, the notches running longitudinally of the clamping section. A side of each notch in an end of the clamping section of the cross-head is undercut 25 forming a tongue 2c.

The socket section of the cross-head receives 30 the end of the mopstick handle. The spring 3 surrounds the socket section and the lower portion of the mopstick handle. To the last convolution of this spring the lever 4 is secured, the lever having two wings to which the ends of legs 35 5a of the bail 5 are pivotally secured. The legs 5a of the bail extend from the lever and through the notches in the ends of the clamping section of the cross-head. The lever is mounted on the same side of the mopstick handle as the undercut 40 sides of the notches which receive the bail member. In the closed position of the mopstick head, as shown in full lines in the drawing, the tongue 45 2c enters the plane of the bail. In opening the mopstick head, that is, in all positions of the operating lever other than the closed position of 50 the mopstick head, the ends of the legs secured to the lever are removed from the plane of the mopstick handle by a distance equal to substantially half the lever. This causes the plane of the 55 bail to be inclined to the plane of the mopstick handle which includes the clamping section of the cross-head. In such inclined position, shown in broken lines in Fig. 2, the legs of the bail are fully received in the undercut recesses in the sides of the notches of the clamping section of the 55

cross-head and can not be accidentally displaced or disconnected from the head, irrespective of the amount of play of the bail member relative to the cross-head.

5 The bail member is readily and easily assembled on the head, when the mopstick is not in the head, by tilting the bail member with respect to the head.

It is obvious that various changes may be made 10 by those skilled in the art in the details of the embodiment of my invention disclosed in the drawing and described immediately above within the principle and scope of my invention as expressed in the appended claims.

15 I claim:

1. In a mopstick of the type including a bail operating lever pivotally secured to the mopstick handle and a single bail member pivotally secured to the operating lever, a cross-head including 20 a socket for the mopstick handle and a transverse clamping section; the feature of novelty which consists in the transverse clamping section of the cross-head having a notch at each end to receive the bail and an undercut in that side of each notch which is located on the same side of a plane containing the center line of the transverse section of the cross-head and the axis of the mopstick handle as the bail operating lever which undercuts receive the bail member upon 25

moving the bail operating lever away from the mopstick handle and the tongues formed by the undercuts extending at an acute angle to the plane containing the center line of the transverse section of the cross-head and the axis of the mopstick handle. 5

2. In a mopstick of the type including a bail operating lever pivotally secured to the mopstick handle and a single bail member pivotally secured to the operating lever, a cross-head including a socket for the mopstick handle and a transverse clamping section; the feature of novelty which consists in the transverse clamping section of the cross-head having a notch at each end to receive the bail and an undercut in that side of each notch which is located on the same side of a plane containing the center line of the transverse section of the cross-head and the axis of the mopstick handle as the bail operating lever and the tongues formed by undercutting the side edges of the notches extending at an angle of substantially 45 degrees to the plane containing the center line of the transverse section of the cross-head and the axis of the mopstick handle and the tongues being of such length as to prevent the insertion of the bail into the notches if extended at right angles to the aforementioned plane. 10 15 20 25
